CLAIM

The ornamental design for a base for a clean energy information kiosk, as shown and described.

DESCRIPTION

FIG. 1 is a left and front perspective view of a base for a clean energy information kiosk showing our new design in environmental use.

FIG. 2 is a right front perspective view thereof.

FIG. 3 is a front elevation thereof.

FIG. 4 is a rear elevation thereof.

FIG. 5 is a left side elevation thereof. The right side elevation being a mirror image of the left side elevation; and,

FIG. 6 is a top plan view thereof.

The broken lines shown represent unclaimed subject matter and form no part of the claimed design.
